R. LINKLETTER:
BASE FOR CONCRETE STRUCTURES.
APPLICATION FILED OCT. 7, 1915.

1,203,757.

Patented Nov. 7, 1916.

The drawing shows a rectangular metal plate with a grid of 60 circular holes. The holes are arranged in a 10x6 grid. Several features are labeled with numbers:

- 18: A vertical strip on the left edge.
- 12: A curved strip on the top right edge.
- 5: A vertical strip on the right edge.
- 7: A vertical strip on the bottom right edge.
- 6: A curved strip on the bottom left edge.
- 14: A vertical strip on the far right edge.
- 16: A vertical strip on the left edge, below 18.
- 15: A vertical strip on the bottom edge, below 6.
- 9: A curved strip on the top edge, below 12.
- 10: A curved strip on the bottom edge, below 15.

UNITED STATES PATENT OFFICE.

ROBERT LINKLETTER, OF JERSEY CITY, NEW JERSEY, ASSIGNOR, BY DIRECT AND MESNE ASSIGNMENTS, OF ONE-THIRD TO HIMSELF AND TWO-THIRDS TO GEORGE W. MUTTART, OF JERSEY CITY, NEW JERSEY.

BASE FOR CONCRETE STRUCTURES.

1,203,757.

Specification of Letters Patent.

Patented Nov. 7, 1916.

Application filed October 7, 1915. Serial No. 54,486.

To all whom it may concern:

Be it known that I, ROBERT LINKLETTER, a citizen of the United States, residing at Jersey City, in the county of Hudson and 5 State of New Jersey, have invented new and useful Improvements in Bases for Concrete Structures, of which the following is a full, clear, and exact description.

My invention relates to the art of building, my more particular purpose being to provide a framework known in this art as a base, upon which concrete or other plastic material is spread and allowed to set, so as to form a wall, partition, ceiling, floor or 15 the like.

My invention further contemplates an improved form of board, made of concrete or other material originally in a plastic form, this board, because of its shape and 20 structure, being especially adapted to be built into and form a part of the base just mentioned.

Reference is made to the accompanying drawing forming a part of this specification, and in which like letters indicate like parts in all of the figures.

Figure 1 is a section through a partly-finished wall made in accordance with my invention, and is taken on the line 1—1 of 30 Fig. 3, looking in the direction indicated by the arrows. Fig. 2 is a view showing one of the boards, partly in plan and partly broken away. Fig. 3 is an elevation of a partly-finished wall constructed in accordance with 35 my invention, certain portions being broken away. Fig. 4 is a perspective of a fastening used for holding the boards in position at all times, but more particularly before the structure is completed.

40 The general form of the board may be understood from Fig. 2. A body member 5 has in general outlines the proximate form of a rectangle, the corners, however being provided with obliquely disposed facets 6. The body member is provided with holes 7 each extending through it and having a frusto-conical form. The body member 5 is further provided with a number of projecting portions 8, each of annular form. These projecting portions virtually increase the thickness of the body member 5, around each hole 7, and in so doing they slightly increase the depth of the holes. They are all disposed upon one face of the 45 50 55 60 65 70 75 80 85 90 95 100 105 board, and encircle the portions of smallest diameter of the holes as indicated in Fig. 1. Each body member 5 is provided adjacent the facets 6, with corner portions 9, which are not provided with holes 7. That is to say the corner portions are each large enough to contain a hole 7, but such hole is omitted. The strength of the board is thus increased, the corner portions especially being strengthened, both by omission of the holes from them and by giving them such form as to avoid sharp angles. The annular projections 8 also strengthen the board, by adding material so as to reinforce it where it would otherwise be weakened by the presence of the holes.

The edge of each hole 7, where bounded by the adjacent annular projection 8, is rounded slightly in its cross section, as indicated in Fig. 1, and the annular projection itself is sloped slightly a short distance from the hole, in order to avoid abrupt bends in the surface of the material.

Each body member 5 carries a sheet of paper 10, which adheres firmly to it. If the body member be made of plaster of Paris, concrete or other plastic material and while soft brought into close contact or under pressure with the paper, the latter adheres firmly and the degree of adhesion increases as the material hardens and sets. The sheet of paper 10 has proper conformity to fit upon the various annular projections 8, and is provided with portions 11 of frusto-conical form extending entirely through the hole and bounding the same. The sheet of paper 10 completely covers one face of the body member 5, and extends flush with the edges thereof. The body member 5 also carries a sheet of waterproof paper 12, which as a rule is not secured to the body member 5 at the time the latter is in a plastic state, but is applied at any time after the body member 5 has set or hardened. Preferably the waterproof paper consists of strong paper saturated with asphalt or thick tar, and thus rendered adhesive so as to cling to the body member. While the length and breadth of the sheet of waterproof paper are the same as the length and breadth of the body member 5, the sheet is displaced slightly in relation to the body member as indicated more particularly in Fig. 2, so as to leave two margins 13 and 14 projecting slightly from,

or slightly over-hanging, the adjacent edges of the body member. This leaves two edges 15, 16 of the body member 5 exposed or uncovered. The sheet of waterproof paper, at the time when it is applied to the body member, has no holes in it. On the contrary it closes the holes 7 at the adjacent ends thereof. That is, it extends across these holes at their portions of maximum diameter.

I provide a few boards 17 which are each of only half the size of the boards above described, and these smaller boards I designate as half-boards. Their use is merely to facilitate the breaking of joints where the boards are used in the construction of a wall or the like, in much the same manner that half-bricks are used at intervals in brick-work in order to stagger the mortar joints thereof. For use in holding the boards together in a wall or the like, I provide metallic fasteners 18, each being of substantially U-form, as shown in Fig. 4. At 19, 20 are shown two layers of plastic material, such as concrete or plaster of Paris, used for the outer surface of the wall or other structure to be built.

In building a wall or analogous structure I arrange the plates edge to edge, so that the margins 13, 14 of one board overlap mating edges 15, 16 of two adjacent boards. In the form of wall shown in Figs. 1 and 2, I place the boards in two groups, the boards in each group being edge to edge and staggered as above described, the boards of one group facing in a direction opposite to those of the other group. That is, the boards of one group all have their annular projections 8 facing in one direction, while the boards of the other group all have their projections 8 facing in the opposite direction. Considering the face of each board as the one provided with the annular projections, the boards of one group are disposed back to back relatively to the boards of the other group. The boards of each group are staggered relatively to those of the other group so as to break joints relatively thereto, and are also arranged so that the holes of one board are nearly but not quite in exact registry with the holes of the adjacent boards of the other group, as shown in Fig. 1. When the plastic material, such as concrete or cement, is afterward spread on as indicated at 19, 20 in this figure, the plastic material fills the holes in the board, and thus forms as many anchorages as there are holes, for the purpose of holding in position the plastic material thus applied.

Where the fasteners 18 are used the waterproof sheets of paper are broken or disrupted as shown at 21, 22, so as to form crater-like openings, through each of which a fastener 18 is extended and then pushed or driven downwardly and caused to straddle

portions of two plates, as shown in Fig. 1. Then, when the soft plastic material is spread on, it fills the holes and envelops the crater-like portions 21, 22 of waterproof paper and thereby makes a very strong anchorage and bond.

The annular projections 8 not only strengthen the boards, but to some extent serve as shelves for supporting the soft material spread over the faces of the plates. The annular projections also increase the firmness of the anchorage between the boards (now formed into a base) and the plastic material spread on, by increasing the difficulty of any accidental sliding movement of the plastic material, especially while in a state of softness, relative to the base made up of the boards.

As the plastic material is spread upon the basic structure, it flows into and fills the triangular openings each formed by two facets 6 and the edge of the board immediately adjacent. The plastic material is thus more firmly anchored upon the basic structure. The fastenings 18 remain in the wall, and thus permanently increase its strength.

The waterproof paper is used principally in instances where the wall is exposed to the action of moisture. The waterproof paper serves also a good purpose in conserving the moisture of the concrete, cement or other plastic material spread upon the basic structure. That is to say, when the plastic material is spread on it contains water, and if this water makes its escape by oozing through the joints or fissures of the basic structure, or even is taken up by capillarity of some adjacent portion of the wall, the setting of the plastic material is unduly quickened and the result is not satisfactory. By use of the waterproof paper the moisture is retained within the plastic material until the latter has adequate time to set.

As the various boards or building units may be arranged in many different ways, I do not limit myself to the particular grouping shown. Neither do I limit myself to the exact construction shown for the board or building unit, the scope of my invention being commensurate with my claims.

I claim:

1. In a device of the character described the combination of a plurality of boards disposed in groups and each provided with anchor holes, the boards of one group being staggered relatively to the boards of another group, a number of fastening members each engaging a board of each of the two groups and extending through the anchor holes thereof, and a quantity of plastic material adhering to said boards and filled into said anchor holes thereof, so as to conceal said fastening members.

2. A building unit, comprising a flat body member provided with anchor holes and

with thickened portions encircling said anchor holes and extending slightly from the face of said body member.

3. A building unit, comprising a flat body member provided with anchor holes of substantially frusto-conical form extending through it and with annular projections each encircling a hole and extending integrally a slight distance outwardly from the face of the board.

4. A base for concrete structures comprising a number of boards disposed edge to

edge, each board being provided with anchor holes and with projecting portions encircling said holes and extending integrally from the faces of said boards, and a quantity of plastic material spread over said boards and partially resting upon said projecting portions, said plastic material extending integrally into said anchor holes.

In testimony whereof I have signed my name to this specification.

ROBERT LINKLETTER.
